(57) **CLAIM**

I claim the ornamental design for a rodent repellent, as
shown and described.

DESCRIPTION

FIG. 1 is an upper front perspective view of our new design;
FIG. 2 is an upper rear perspective view thereof;

FIG. 3 is a top plan view thereof;

FIG. 4 is a front elevational view thereof;

FIG. 5 is a left elevational view thereof;

FIG. 6 is a right elevational view thereof;

FIG. 7 is a rear elevational view thereof; and,

FIG. 8 is a bottom plan view thereof.

The broken lines are for the purpose of illustrating portions
of the article and form no part of the claimed design.
